201,398

COMBINED STACKING BOX AND COVER THEREFOR

Atwill B. Burns and William G. Lachapelle, both of Portland, Oreg., assignors to Playthings, Inc., Portland, Oreg., a corporation of Oregon

Filed Mar. 3, 1964, Ser. No. 78,857

Term of patent 14 years

(Cl. D58—12.6)

We claim:

The ornamental design for a combined stacking box and cover therefor, substantially as shown.
